CONTINUOUS ROLLING MILL

John W. Sheperdson, Worcester, Mass., assignor
to Morgan Construction Company, Worcester,
Mass., a corporation of Massachusetts

Application March 3, 1947, Serial No. 732,034

3 Claims. (Cl. 80—35)

1

This invention relates to continuous rolling mills, and more particularly to continuous mills arranged for the hot rolling of metal bars and commonly known as "merchant" mills, although the invention may be applicable in certain respects to other types of continuous mills.

The usual merchant mill includes a plurality of roll stands through which the bar travels successively, the spacing and arrangement of the roll stands being such that the bar will extend through several or all of the stands simultaneously. It is customary to form a loop in the bar between certain stands in order to relieve the bar of tension. If the loop is allowed to grow freely a considerable space must be provided to accommodate such growth. Accordingly in some instances the size of the loop has been controlled by means of regulating apparatus actuated automatically by the looped bar itself. In general however such prior apparatus has been of a delicate and flimsy construction likely to be rendered inoperative by scale from the bar or by direct mechanical damage in the event of a cobble.

It is accordingly one object of the invention to provide a continuous rolling mill having provision for forming a loop in the bar between two successive roll stands, and a thoroughly dependable apparatus for automatically controlling the size of the loop.

It is a further object of the invention to provide a continuous rolling mill having a series of roll stands with looping tables between successive stands, and control apparatus for regulating the speeds of the roll stands in accordance with variations in the sizes of the adjacent loops, the control apparatus being of a rugged construction which will be unaffected by mill scale and undamaged by cobbles.

With these and other objects in view, as will be apparent to those skilled in the art, the invention resides in the combination of parts set forth in the specification and covered by the claims appended hereto.

Referring to the drawings illustrating one embodiment of the invention and in which like reference numerals indicate like parts,

Fig. 1 is a somewhat diagrammatic plan view of a continuous rolling mill;

Fig. 2 is an enlarged plan view of a part of the mill, showing the front portion of a bar traveling from one roll stand to the next;

Fig. 3 is a view similar to Fig. 2, showing the position of the parts after a loop has been formed in the bar;

Fig. 4 is an enlarged section taken approximately on the line 4—4 of Fig. 2;

2

Fig. 5 is an enlarged section taken approximately on the line 5—5 of Fig. 3;

Fig. 6 is an enlarged section taken approximately on the line 6—6 of Fig. 2;

Fig. 7 is an enlarged section taken along approximately on the line 7—7 of Fig. 2; and

Fig. 8 is an electrical wiring diagram showing a means for controlling the speed of one roll stand.

In Fig. 1 there is shown diagrammatically a plurality of roll stands 10, 11, 12, 13 and 14 arranged in a longitudinal row so that a metal bar may pass through them in succession. These roll stands are driven by electric motors 16, 17, 18, 19 and 20 respectively. As shown, the roll stands are alternately horizontal and vertical, so that twist guides are not required. Between each pair of successive roll stands there is provided a substantially horizontal table 22 on which a loop 15 may form in the bar, in order that the bar may be rolled without appreciable tension.

One of these looping tables 22 is shown on a larger scale in Figs. 2 and 4. It will be seen that an upstanding flange 24 is formed on the table 25 along the outer side of the path of the bar B as it travels in a direct line from one roll stand 11 to the receiving guide 25 of the following roll stand 12. The table is preferably slightly inclined upwardly away from this flange. On the inner side of the path of the bar there is provided a row of guide blocks 26 which are arranged to project upwardly through openings 27 in the table. These blocks 26 are connected to one another beneath the table to form an integral unit 30 or member 29. This member is provided with ears 31 (one only being shown) which are pivotally supported on a horizontal rod 32 (Fig. 4) beneath the flange 24. An arm 33 extends downwardly from the member 29, and a link 34 connects this arm to the slidably piston rod 35 of a suitable fluid motor 36. These parts are so constructed and arranged that after the front end of the bar B has entered the roll stand 12, the member 29 may be swung downwardly, as shown in Fig. 5, to permit the bar to move over the tops of the blocks 26 and form a loop on the table 22.

In order to assist in the formation of the loop, the flange 24 is shaped to provide a pocket 37 (Figs. 2 and 6) for the reception of a yoke 38 which carries an upright idler roller 39 positioned at the outer side of the path of the bar, near the entrance end of the looping table. This yoke 38 is pivotally supported by a vertical pin 40 beneath the table, and the table is provided with an opening 41 within which the roller 39 may travel as the yoke is moved about its pivot. Such move-

ment of the yoke may be brought about by a fluid motor 43 having a slideable piston rod 44 which is connected to the yoke by a link 45.

Upright idler rollers 47 and 48 are mounted on the table 22 at the inner side of the path of the bar, adjacent the entrance and exit ends of the table respectively. These rollers serve as guide devices which avoid scratching of the bar, particularly after the loop has been formed.

The invention provides a means whereby the size of the loop in the bar will be controlled automatically. For this purpose the table 22 is provided with an opening 50 at the inner side of the guide blocks 26. Within this opening there is mounted a group of electrical contact blocks 51, 52, 53, 54, 55 and 56. These blocks are arranged in two rows extending approximately at right angles with the path of travel of the bar, the blocks in one row being staggered with respect to the blocks in the other row, and they project upwardly slightly above the top of the table so that the looped bar may make contact with them. Furthermore, the blocks in each row slightly overlap the blocks in the other row, in a direction lengthwise of the rows, in order that the bar will always be in contact with at least one block while the loop is under automatic control. As shown in Fig. 7, the upper surfaces of the blocks are rounded to avoid scratching of the bar. The blocks are electrically insulated from one another and from the table 22, and for this purpose each block is slotted to fit over the upper portion of an upright plate 58 of electrical insulating material. The lower portions of the plates are secured to beams 59 which are connected to the bottom of the table 22 by suitable brackets 60. Conduits 62 are provided adjacent the beams 59 to enclose wires leading to the separate contact blocks. Depending skirts 63 are provided on the blocks to protect the conduits from damage by cobbles and to prevent short circuits by mill scale which may drop through the opening 50. It will be noted that the blocks are spaced appreciably from one another and from the edge of the opening 50.

In Fig. 8 there is shown diagrammatically certain electrical apparatus whereby the speed of the motor 18 may be controlled automatically, and it will be understood that the speeds of the motors 17, 19 and 20 may be controlled by similar means. The normal speed of each motor is such, in relation to the speed of the motor driving the preceding roll stand, that a loop will start to form and to increase in size as soon as the front end of the bar enters the rolls. The automatic control simply prevents this loop from growing beyond a predetermined size. As shown, the motor 18 is of a well-known type having an armature 65 and a field 66. The armature 65 may be connected to a direct current source 67 through a switch 68. The field 66 may be connected to a direct current source 69 through a switch 70. Resistance units 72, 73, 74, 75, 76 and 77 are connected in series with the field 66, but until the loop in the bar has reached a predetermined size these units are all short-circuited. For this purpose there are provided magnetic contactors having coils 79, 80, 81, 82, 83 and 84 which control normally closed switches 79a, 80a, 81a, 82a, 83a, and 84a respectively, these switches being connected in shunt with the resistance units 72, 73, 74, 75, 76 and 77 respectively. The coils 79, 80, 81, 82, 83 and 84 are connected between a source 86 of positive electrical potential and the respective contact blocks 51, 52, 53, 54, 55 and 56.

The coils 80, 81, 82, 83 and 84 also control normally open switches 80b, 81b, 82b, 83b, and 84b respectively which are connected between the ground at 87 and the respective contact blocks 51, 52, 53, 54 and 55. As indicated at 88, the bar B is grounded by its contact with the various rolls, tables, and the like.

The operation of the invention will now be apparent from the above disclosure. The previously heated metal bar B will travel successively through the roll stands 10, 11, 12, 13 and 14, with a reduction in bar cross-sectional area taking place in each stand. Ordinarily the bar will extend through all of these roll stands during most of the rolling operation. As the front end of each bar leaves the roll stand 11 and reaches the following table 22, as shown in Fig. 2, it will travel in a straight path between the flange 24 on one side and the upwardly projecting blocks 26 on the other side, thereupon passing through the guide 25 and entering the roll stand 12. As soon as this occurs the operator will admit pressure fluid to the fluid motors 35 and 43, thereby lowering the guide blocks 26 (as indicated in Fig. 5) and swinging the idler roller 39 to the position shown in Fig. 3, thereby forming a loop in the bar on the table 22. As the loop starts to form, the motor 18 will be operating at a relatively low speed, since the switches 79a to 84a inclusive will all be closed, thus shunting the resistance units 72 to 77 inclusive, and producing a relatively strong field 66, the switches 68 and 70 of course being closed. Accordingly the loop will continue to increase in size and move outwardly across the table 22 until it makes contact with the block 51 and grounds the same. This will establish a circuit from the source 86 through the coil 79 to ground, energizing this coil and opening the switch 79a, thereby rendering the resistance unit 72 effective to reduce the energization of the field 66 and increasing the speed of the motor 18 slightly. This will reduce the rate of growth of the loop, but ordinarily it will nevertheless continue to grow until it makes contact with the next block 52, grounding this block and energizing the coil 80. This will open the switch 80a and close the switch 80b. Opening the switch 80a will render the resistance unit 73 effective to speed up the motor 18 still further, and closing the switch 80b will maintain a circuit through the coil 79 even after the loop has moved outwardly out of contact with the block 51. If the loop still continues to grow, it will make contact with the block 53 and ground the same, thus energizing the coil 81, opening the switch 81a and closing the switch 81b. This will render the resistance unit 74 effective to increase the speed of the motor 18 still further and at the same time maintain a circuit through the coil 80 even after the loop has moved outwardly out of contact with the block 52. In a similar manner, if the loop nevertheless continues to grow, it will ground the block 54, then the block 55, and possibly even the block 56, which will result in shunting all the resistance units 72 to 77 inclusive and surely provide sufficient speed for the rolls 12 to reduce the size of the loop.

Any appreciable reduction in the size of the loop will result in a slowing down of the rolls 12. Thus if the loop moves inwardly out of contact with the block 56 and into contact with the block 55, the coil 84 will be de-energized, closing switch 84a and opening switch 84b. This will shunt the resistance unit 77 and cause a corresponding decrease in the speed of the motor 18. Opening

the switch 84b will ensure the de-energization of the coil 83 in the event the loop moves inwardly out of contact with the block 55. Thus any variation in the size of the loop will cause a change in the speed of the rolls 12 tending to oppose such variation, and the loop will remain within the size limits determined by the positions of the inner and outer blocks 51 and 56 respectively. As soon as the rear end of the bar has left the looping table, the operator will restore the guide blocks 26 and the roller 39 to their original positions by means of the motors 35 and 43, in preparation for the arrival of the next bar. The several looping tables 22 may all be similar in construction and mode of operation.

It will be apparent that the invention provides a simple and dependable continuous rolling mill in which bars may be rolled without tension. Loops are formed between successive roll stands, and these loops are controlled by automatically varying the speeds of the roll stands. This automatic control is brought about by engagement of the bar with contact blocks so arranged that the bar itself forms a portion of an electrical control circuit. These blocks are constructed and mounted in a rugged manner, and they are very unlikely to be damaged by cobbles. Any loose scale which may drop from the bar as it travels across the blocks is free to fall through the opening 50 in the table without causing short circuits or other difficulties. The slight inclination of the table 22, shown in Fig. 5, is helpful in maintaining good electrical contact of the bar with the blocks.

Having thus described my invention, what I claim as new and desire to secure by Letters Patent is:

1. A continuous rolling mill comprising a first and second roll stand through which a metal bar may travel successively and thereby be subjected to successive reductions, a substantially horizontal looping table located between the roll stands, means to drive the roll stands at such relative speeds as to cause a portion of the bar to accumulate between the stands, means to deflect the portion of the bar between the stands in a lateral direction and thereby form a loop in the bar in a substantially horizontal plane on the table, a series of stationary blocks associated with the table and electrically insulated from the table and from one another, the upper surfaces of the blocks being located slightly above the upper surface of the table, the blocks being in position to be engaged successively by the looped bar and thereby be electrically grounded as the loop increases in size and the bar travels over the tops of the blocks, means responsive to the grounding of the successive blocks to alter the speed of one of the roll stands successively in a manner tending to limit the growth of the loop, and a guide associated with said table for directing the bar toward the second roll stand, and means retracting the guide to permit said loop to be formed by said deflecting means after the bar has reached the second roll stand.

2. A continuous rolling mill comprising a pair of roll stands through which a metal bar may travel successively and thereby be subjected to

successive reductions, a substantially horizontal looping table located between the roll stands, means to drive the roll stands at such relative speeds as to cause a portion of the bar to accumulate between the stands, means to deflect the portion of the bar between the stands in a lateral direction and thereby form a loop in the bar in a substantially horizontal plane on the table, a series of stationary blocks associated with the table and electrically insulated from the table and from one another, the upper surfaces of the blocks being in position to be engaged successively by the looped bar and thereby be electrically grounded as the loop increases in size and the bar travels over the top of the block, and means responsive to the grounding of the successive blocks to alter the speed of one of the roll stands successively in a manner tending to limit the growth of the loop, said table being provided with an opening to receive the blocks, the blocks being spaced from one another and from the edge of the opening so that mill scale may readily drop through the opening.

3. A continuous rolling mill comprising a pair of roll stands through which a metal bar may travel successively and thereby be subjected to successive reductions, a substantially horizontal looping table located between the roll stands, means to drive the roll stands at such relative speeds as to cause a portion of the bar to accumulate between the stands, means to deflect the portion of the bar between the stands in a lateral direction and thereby form a loop in the bar in a substantially horizontal plane on the table, a series of stationary blocks associated with the table and electrically insulated from the table and from one another, the upper surfaces of the blocks being located slightly above the upper surface of the table, the blocks being in position to be engaged successively by the looped bar and thereby be electrically grounded as the loop increases in size and the bar travels over the tops of the blocks, means responsive to the grounding of the successive blocks to alter the speed of one of the roll stands successively in a manner tending to limit the growth of the loop, and a guide located between the direct line of bar travel from one stand to the other and the stationary blocks, the guide providing a barrier to prevent lateral movement of the bar toward the blocks, means being provided whereby the guide may be lowered after the front end of the bar has reached the second bar to allow formation of the loop.

JOHN W. SHEPERDSON.
